UNITED STATES PATENT OFFICE

2,107,285

ICE TRAY SUPPORTING AND RELEASING MEANS

Arthur R. Constantine, River Forest, Ill., assignor, by mesne assignments, to Reconstruction Finance Corporation, Chicago, Ill., a corporation

Application February 23, 1934, Serial No. 712,563

15 Claims. (Cl. 62—108.5)

5 My invention relates in general to refrigerators and more particularly mechanical refrigerating apparatus wherein a receptacle, such as an ice cube tray, containing water or other material to be chilled is carried on a support in position to be refrigerated; and an important object of the invention is to provide means for releasing the receptacle from its support in order to facilitate its removal.

10 Another important object is to provide simple release means mounted on the receptacle support and manually operable to separate the tray or receptacle from its support by breaking the ice bond which tends to form between the receptacle and its support through the freezing of condensed or other moisture therebetween.

15 Another important object is to provide a release means operable to raise one end of the tray from its support in order to break an ice bond between tray and support; a further object being to form the release means as a wedge adapted to enter between the tray and its support for the purpose of separating the frozen parts.

20 Another object is to provide a manually operable tray release having an operating handle disposed in position, at one side of the tray support, to facilitate manipulation of the release without obstructing the removal of the tray from the support.

25 Another object is to provide a tray release pivoted on the tray support and having an operating handle extending to the side of the support and a wedging portion opposite an end of the tray in position to enter between the tray and its support to separate the same when the handle is manipulated; a further object being to form the release as a relatively flat member over which the tray may pass without obstruction.

30 Another object is to provide a tray support and release which may be formed as a unit for assembly in a refrigerator casing; a further object being to form the tray support as a single sheet metal element.

35 Another important object is to provide a removable tray support adapted for mounting within a housing such as the evaporator element of a refrigerator, the support being formed with holding means adapted to interfit with portions of the evaporator element to hold the support in tray-carrying position within the element; a further object being to form the holding means as an integral part of the tray support and more particularly to form the tray as a unitary sheet metal member in which the holding means comprise struck out lugs.

40 My invention further includes numerous other objects, advantages and inherent functions, not specifically mentioned herein, which will become apparent as the invention is more fully understood from the following description which, taken with the accompanying drawing, discloses a preferred embodiment of the invention.

Referring to the drawing:

45 Figure 1 is a perspective view of a refrigerating element carrying tray supports including tray release means embodying my present invention;

50 Figures 2 and 3 are perspective views of parts of the refrigerating element shown in Figure 1;

55 Figures 4, 5, and 6 are sectional views taken substantially and respectively along lines 4—4, 5—5, and 6—6 in Figures 8, 4 and 1 respectively;

60 Figure 7 shows the refrigerating element as mounted in a refrigerator cabinet; and

65 Figure 8 is a perspective view of a support shelf and attached tray release.

70 To illustrate my invention, I have shown on the drawing a refrigerator element 11, in which a shelf 12 is mounted in position to receive a container or pan 15 adapted to contain material to be refrigerated. The refrigerator element 11 may be of any suitable form, construction, or arrangement providing for the mounting of the shelf but I have shown it in the form of an evaporator or boiler which is connected in a refrigerant circulating system including a refrigerant compressor 17, 75 drivingly associated with motive means 19, the discharge outlet of the compressor being connected through a refrigerant condenser 21, and a float-controlled expansion valve 23 to the inlet of the evaporator 11. In this type of refrigerating system, the refrigerating medium in gaseous condition is drawn into the compressor through conduit means 25 connecting with the evaporator discharge and is compressed and delivered in gaseous condition under pressure to the condenser in 80 which the refrigerant is cooled and changed to liquid form. From the condenser, the liquefied refrigerant is delivered through the float-controlled valve 23 to the evaporator 11 in which the refrigerant evaporates or boils and changes to the gaseous state while absorbing heat from the walls of the evaporator and the surrounding atmosphere and thus accomplishing the refrigerating function in the vicinity of the evaporator.

85 The evaporator shown comprises a pair of formed plates of channel shaped configuration having spaced side walls and an interconnecting bottom wall, said plates being adapted to fit one within the other. The outer plate 27 has outwardly formed impressions including semi-cy-

cylindrical depressions 29 near the upper edges of its side walls and a plurality of grooves 31 extending in the side and bottom walls and interconnecting the depressions 29. The inner plate 33 has inwardly pressed semi-cylindrical depressions 35 near the upper edges of its side walls in position to register with the depressions 29 when the parts are assembled in interfitting relationship in order to form gas receiving chambers from which the evaporated refrigerant is drawn off through the pipe 25. The side walls of the plate 33 are also formed with inwardly extending ridges 37, the ridges on opposite side walls of the plate being in horizontal registration. The plates are secured together in interfitting relationship by sealing their adjacent edges in any suitable fashion, as by welding, in order to form, between the plates, a gas-tight evaporating chamber comprising the spaces defined by the depressions 29 and 35 and the ridges 31 and 37. The evaporator inlet connection is formed preferably on one of the ridges 37 and the finished structure may be strengthened by securing a connector 39 between the pressed portions 35 of the inner plate. The plates are preferably additionally secured together as by means of welding applied intermediate the ridges 31 and 37.

The refrigerating unit 11 and the other elements of the refrigerating system if desired may be arranged in a refrigerator cabinet of any suitable or preferred construction.

The shelf 13 may be formed in any suitable or convenient manner and secured in the refrigerator in heat exchange relationship with the evaporator unit 11. The shelf, however, is preferably formed for interfitting engagement with the registering ridges 37 which extend inwardly of the side walls of the unit 11 so that the shelf may be mounted quickly and easily without additional fastening means and may as easily be removed in order to facilitate cleaning. To this end, I prefer to form the shelf as an integral sheet metal element comprising a plate 41 having struck-out lugs 43 at its opposite side edges, said lugs being curled to slidably fit upon the ridges 37 of the evaporator unit. The side edges of the plate 41 are also preferably formed with upstanding flanges 45 adapted to bear against the inner wall surfaces of the unit 11 in order to snugly secure the shelf in position when the same is mounted in the unit 11. The shelf is adapted to form a carrier on which the container 15, or any other article or device, may be mounted in position to be refrigerated. The container may be of any suitable or preferred construction for the purpose of receiving material to be refrigerated, my present invention particularly contemplating a relatively shallow, fluid-tight pan adapted to receive water to be frozen to form ice cubes. The plate 41 near its rearmost edge is or may be provided with means, comprising an upwardly struck lip 47, in position to engage the pan in order to limit its rearward travel on the shelf and the plate 41 may be formed with laterally extending beads 49 and longitudinal depressions 51 increase the strength of the shelf and for drainage purposes.

In the operation of refrigerators, moisture is likely to condense upon the shelf 13 and to form a frozen seal between the bottom of the container 15 and the shelf surface 41 under the refrigerating action of the unit 11 when the same is in operation. The container 15 may thus become so tightly frozen upon the shelf as to render its

removal difficult and to this end I have provided a breaker mechanism which is preferably mounted on the shelf and conveniently located to facilitate manual operation to break the frozen bond and loosen the container from the shelf in order to permit the same to be easily removed from the freezing unit 11. For this purpose, I have provided a breaker element comprising a member 53 pivoted on the forward portions of the shelves 41 or on the bottom wall of the unit 11, which also may act as a shelf. The members 53 may each be secured in position by means of a pin 55 and each has an operating handle 57 extending adjacent a side edge of the shelf on which it is attached.

The refrigerator unit 11 is preferably arranged in the cooling compartment 12 of a suitable refrigerator cabinet 10 having an opening provided with a suitable closure or door 14, one end of the unit 11 facing the door opening, through which access is or may be had to the cooling compartment, and said unit 11 being arranged in the compartment so that its forward end faces the compartment opening whereby when said door is opened, access may readily be had through the compartment door opening to the containers 15 and to the breaker means in order to facilitate operation of the breaker means and permit the containers 15 to be readily withdrawn from the shelves 13. Alternately, the unit 11 may itself be formed with a door or other closure means at its forward end whereby to permit access to the breaker means and the containers through an end of the unit, when said closure means is open.

The member 53 is of relatively shallow construction in order to present little, if any obstruction, to the removal of the container 15 from the shelf, the container being slideable over the member 53 without requiring appreciable elevation from its normal resting position on the shelf. When the member is in normal position, there is a substantial space between it and the adjacent edge of the shelf so that there is no danger of the arm becoming frozen to the shelf. The member 53 has a wedge-like portion comprising a blade 59, which is adapted to enter between the bottom of the container 15 and the shelf, as shown in Figure 6, when the breaker is moved from its normally inactive position, shown in full lines in Figure 3, to the ice breaking position illustrated in dotted lines. The wedging action exerted between the shelf and the container 15 by the entrance of the blade 59 between the shelf and the container exerts a powerful lifting action upon the one end of the container 15 and results in effectively destroying the bonding effect of the frozen film of moisture between the container and its supporting shelf, thus freeing the container and permitting it to be readily withdrawn from its supporting shelf.

The shelf also may be curled as at 63 in order to improve the appearance of its forward edge and any suitable yielding means may be provided, if desired, to normally bias the breaker member 53 toward the inactive position whereby to automatically return the handle to the position shown in full lines in Figure 8 after being manipulated to perform the ice breaking function. Such provision of yielding means is not, of course, essential since the breaker may be manually returned to the inoperative position. I do, however, prefer to form the handle with a shoulder or projection 61 in position to engage

a co-operating portion or element 62 formed on or carried by the shelf for limiting the movement of the breaker member in one direction on its pivot and determining its inoperative position. The element 62 may take the form of a lug integrally formed on a washer 65 mounted between the forward edge of the shelf 41 and the ice breaker, and having a perforation receiving the pin 55. The washer also may have a flange 67 curled about the forward edge of the shelf to hold the washer from turning on the pin. The blade 59 also may be and preferably is provided with a shoulder or projection 69 in position to engage a stop on the shelf, such as the stop 62, in order to limit the ice breaking movement of the breaker element and stop it in the position shown in dotted lines in Figure 8.

The breaker mechanism, which I have provided, is extremely simple in construction, cheap to manufacture, and positive in action. It may be mounted as well upon the bottom wall of the unit 11, see Figure 1, as on the shelves 41. Its construction is such that the mounting or removal of the container 15 on or from the shelf 25 is substantially unhampered. The portion of the breaker, over which the tray is moved, is relatively flat, while the handle 57, when the breaker is inactive, is disposed at one side of the shelf in a position permitting unhampered movement 30 of the container.

The shelf also is of simple construction and can be easily and cheaply manufactured by a simple sheet metal stamping operation. In addition the shelf construction, in conjunction with the construction of the unit 11, whereby the shelf 35 may be easily mounted on the unit without requiring additional fastening means has great utility, more especially because the shelf may be arranged selectively at any desired elevation in 40 the unit 11 or may be entirely removed by simply withdrawing it from mounted position, thus permitting considerable latitude in the arrangement of the cooling space within the unit 11. One or more shelves may be mounted and thus permit 45 the reception of containers of a variety of sizes in a refrigerator unit of standardized form, and a further advantage resides in the ability to quickly remove any or all shelves from the unit in order to leave the interior of the unit entirely 50 unobstructed and thus facilitate cleaning operations as well as permit the unit to receive a container of maximum size which is not possible where the shelves are permanently mounted or mounted in a fashion rendering removal difficult.

55 Numerous other objects, advantages and inherent functions of the invention will be apparent, from the foregoing description, to those familiar with the art of refrigeration and it will be obvious that numerous changes may be 60 made in the form, construction, and arrangement of the several parts without departing from the spirit or scope of my invention or sacrificing any of its attendant advantages; the forms herein described being preferred embodiments for 65 the purpose of illustrating my invention.

What I claim as new and desire to secure by Letters Patent is as follows:

1. The combination with a cooling device having supporting means adapted to carry support- 70 able means in heat-exchange relationship with said cooling device, of means comprising a wedge carried by said supporting means and shiftable thereon between said supporting and supportable means in order to break an ice bond therebe- 75 tween.

2. The combination with a cooling device having supporting means adapted to carry supportable means in heat-exchange relationship with said cooling device, of means comprising a knife blade pivoted on said supporting means, and manually operable means to turn said knife blade about its pivot in a direction to enter between the supporting and supportable means in order to break an ice bond therebetween. 5

3. The combination with a cooling device hav- 10 ing supporting means adapted to carry supportable means in heat-exchange relationship with said cooling device, of a handle pivoted on said supporting means, and means associated with said handle and adapted, when said handle is 15 shifted, to enter between the supporting and supportable means to break an ice bond therebetween.

4. The combination with a cooling device hav- 20 ing support means adapted to carry supportable means in heat exchange relationship with said cooling device, of a release lever pivotally mounted on said support means for movement about a vertical axis, said lever being adapted to extend normally in position permitting free access 25 to said supportable means, said lever also having a portion adapted, when the lever is moved from its normal position, to enter between said support and supportable means in order to break 30 an ice bond therebetween.

5. The combination with a cooling device hav- 35 ing a shelf for supporting a container in said device, said device and shelf being formed to permit removal and replacement of said container across an edge of said shelf, of a lever pivotally mounted on said shelf at or adjacent said edge, said lever being mounted for pivotal movement about a vertical axis and having a handle to facilitate manual operation thereof, said lever being adapted to extend in position with its 40 handle in substantial alinement with said edge whereby to avoid obstructing removal or replacement of said container, said lever having a portion adapted, when the lever is moved from said normal position, to enter between said shelf and said container to break an ice bond therebetween. 45

6. The combination with a cooling device hav- 50 ing a shelf adapted to carry a container in heat exchange relationship with said cooling device, a handle pivoted on said shelf, and means associated with said handle and adapted, when said handle is shifted, to enter between the shelf and the container to break an ice bond therebetween, said means being adapted normally to lie out- 55 wardly of and opposite the ice bond.

7. A shelf structure for supporting a container in heat exchange relationship with a cooling de- 60 vice, a handle pivoted on said shelf adjacent an edge thereof, and means associated with said handle and adapted, when said handle is shifted, to enter between the shelf and the container in order to break an ice bond therebetween, said means being adapted normally to lie outwardly 65 of and opposite the ice bond.

8. The combination with a cooling device, hav- 70 ing supporting means adapted to carry supportable means in heat exchange relationship with said cooling device, of breaker means carried by said supporting means and operable to break an ice bond between the supporting and supportable means, said breaker means comprising a relatively shallow element mounted in position to enter between the supporting and supportable means and permitting substantially unhampered 75

relative sliding movement between the supporting and supportable means.

9. The combination with a cooling device, having supporting means adapted to carry support-

- 5 able means in heat-exchange relationship with said cooling device, of a bell crank lever pivoted on said supporting means and having an arm formed as a handle extending at one side of the supporting means and another arm extending 10 into position to enter between the supporting and the supportable means when said handle is moved in order to break an ice bond between the supporting and supportable means.

10. The combination with a freezing compartment

- 15 having a freezing tray therein adapted to be periodically removed, of swingable wedging means operable about a vertical pivot axis with a wedging action between the compartment bottom and the bottom of the tray to release the latter from frozen connection therein.

11. The combination with a freezing compartment and a tray arranged therein, of a lever pivotally mounted on a vertical pivot and operating a cam with a slow powerful wedging action 25 under the tray to release the same from its frozen contact, with the compartment.

12. A refrigerating apparatus including an evaporator shelf, an ice cube tray removably supported on said shelf, and means between the shelf 30 and tray to break the adhering ice seal or bond existing therebetween, said means comprising a stud member, a cam member adapted for rotation around said stud and having a surface normally flush with the contacting surfaces of the shelf and tray, and a handle for rotating the cam about the stud to force the tray out of contact with said shelf.

13. A refrigerating apparatus including an evaporator shelf, an ice cube tray removably sup-

ported on said shelf, and means between the shelf and tray to break the adhering ice-seal or bond existing therebetween, said means comprising a horizontal lifting cam having an inclined cam surface, said cam being mounted for rotation about a vertical axis, the high portion of said inclined cam surface being normally out of engagement with the shelf and tray, and means for rotating said cam about its vertical axis to force the high portion of the inclined cam surface between the shelf and tray to force the tray out of contact with said shelf.

14. In the combination with a freezing unit having a supporting element and a freezing tray element adapted to be periodically removed, oscillatable wedging means pivoted on one of said elements for oscillation about a vertical axis, said means comprising a handle portion and a portion exerting a wedging action between the supporting element and the tray element thereby to release the latter from frozen connection with the former.

15. A refrigerating apparatus comprising an evaporator shelf element, an ice cube tray element removably supported on said shelf element, and means between the shelf element and tray element to break the adhering ice bond existing therebetween, said means comprising a stud member secured to and extending vertically from one of said elements, a cam member adapted for rotation around said stud and having a surface normally flush with the contacting surfaces of the shelf and tray and a handle extending outwardly from said cam member and lying in the plane of the cam member for rotating the same 35 about the stud to force the tray element out of contact with the shelf element.

ARTHUR R. CONSTANTINE.
